UNITED STATES PATENT OFFICE.

EDWARD BOEHM, OF DULUTH, MINNESOTA.

DESIGN FOR A BABY WALKER.

Application filed January 26, 1928. Serial No. 25,042. Term of patent 7 years.

To all whom it may concern:

Be it known that I, EDWARD BOEHM, a citizen of the United States, residing at Duluth, in the county of St. Louis and State of Minnesota, have invented a new, original, and ornamental Design for Baby Walkers, of which the following is a specification, reference being had to the accompanying drawing, forming part thereof.

The figure is a perspective view of a baby walker, showing my new design.

I claim:

The ornamental design for a baby walker, as shown.

EDWARD BOEHM.
